HYDRAULICALLY OPERATED SCRAPER AND
THE LIKECharles Le Bleu, Los Angeles, Calif., assignor to
Emsco Derrick and Equipment Company, Los
Angeles, Calif., a corporation of California

Application May 21, 1935, Serial No. 22,528

8 Claims. (Cl. 37—144)

This invention relates to a material moving means, and particularly pertains to a hydraulically operated scraper or the like.

In the operation of scrapers, such as those used for moving dirt and grading roads, or other areas, it is desirable to move a scraper blade in a manner to insure that it may be freely moved and controlled, and it is further desirable to provide means whereby the scraper blade may be easily raised and lowered or tilted at angles to the horizontal. It is the principal object of the present invention to provide a power propelled scraper structure carrying a scraper blade, which blade is provided with hydraulic operable means to positively raise and lower the blade and to positively tilt it at angles to the horizontal as well as dispose the blade at an inclination to a normal plane of operation at right angles to the longitudinal axis of the structure.

20 The present invention contemplates the provision of a self-propelled vehicle preferably provided with a running gear comprising track laying structures and which vehicle carries a scraper blade disposed transversely of the front thereof, said blade being mounted in a manner to move bodily in a vertical direction, to be tilted with relation to the horizontal, and to be disposed at various inclinations to the path of travel of the vehicle whereby the operating level of the 25 blade will be determined and whereby the material may be shovelled to a desired side of the path of advance of the scraper.

The invention is illustrated by way of example in the accompanying drawings in which:

30 Figure 1 is a view in side elevation showing an embodiment of the present invention.

Fig. 2 is a view in plan showing the structure and particularly the valve arrangement.

35 Fig. 3 is an enlarged view showing the flow plan of the valve arrangement and the hydraulic 40 system.

Referring more particularly to the drawings 45 10 indicates the main frame of the structure which is here shown as carrying a power unit generally indicated at 11. At the rear of the frame 10 is disposed a suitable seat 12 for the operator of the scraper. The main frame is carried upon a pair of track laying units 13 and 14, each of which embodies a rear sprocket wheel 15, a front sprocket wheel 16, a frame structure 17, and an endless track 18. It will be understood that the track laying units are pivotally mounted upon a rear axle 19 which is carried by the main frame 10 and around the opposite 50 ends of which axle the track laying units may

have separate vertical swinging movement as is necessary to accommodate the units to the contour of the ground over which the scraper passes. Disposed at opposite sides of the track laying units are thrust rails 20 and 21. These rails connect with a cross bolster 22 at their rearward ends and thus form a U-shaped frame structure which extends transversely of the front of the tractor and rearwardly along opposite sides thereof. The rear ends of the thrust bars 20 and 21 are provided with pivots 23 and 24 respectively which are connected with opposite ends of an equalizing bar 25 which extends transversely of the rear of the tractor and is pivoted by a center bolt 26 to a bracket 27 fixed to the rear of the tractor main frame. Mounted upon the cross bolster 22 is a king pin 28 engaging brackets 29 extending rearwardly from a transversely disposed scraper blade 30. The scraper blade 30 is thus free to swing horizontally with relation to the pin 28. The frame 17 of the track laying units 13 and 14 carry rigid upright posts 31 at the upper ends of which pivot pins 32 are mounted. These pins provide a pivotal connection for the rear ends of lever arms 33 which extend forwardly and at their outer ends carry a pivot pin 34. The pivot pin 34 of the lever arm 33 associated with the track laying unit 14 receives a bell crank 35, while a similar pivot pin upon the opposite side of the tractor 30 receives a bell crank 36. The lower legs of the bell cranks 35 and 36 are of the same length and extend forwardly and downwardly. The upper legs are of different lengths. The upper leg of bell crank 36 is longer than the same leg of bell 35 crank 35 for a purpose to be hereinafter explained. The forward legs of each of these bell cranks carry pivot pins 37 from which links 38 are suspended. The links hang downwardly and are connected to the cross bolster 22 by pins or bolts 39 and brackets 40 carried by the bolster. The lever arms 33 are pivotally connected at their forward ends to links 41 which are secured to the levers by pins 42 and to the frame 17 of each of the track laying units by pins 43. It will be evident that swinging movement of the bell cranks 35 and 36 will tend to raise and lower the opposite sides of the cross bolster 22. Power is applied to swing the bell cranks 35 and 36 by means of a pair of hydraulic rams 44 and 45 respectively. These rams are of the same cross sectional area and capacity and are so connected as to insure that a pressure fluid delivered to one end of one ram will displace fluid from the opposite end of the same ram and deliver it to 50 55

an end of the other ram, after which said fluid will be displaced from the second ram. It will be evident, however, that the amounts of fluid displaced from the ends of the rams in which 5 the piston rods extend will be less than the fluid capacity of the closed end of each of the rams. This would cause unequal movement of the bell 10 cranks 35 and 36, and for that reason the upper leg of the bell crank 36 is made longer than the leg of the bell crank 35 to compensate for the 15 variation in fluid capacity at opposite sides of the pistons in the hydraulic rams 44 and 45. It will be understood that each of the rams 44 and 45 is provided with a piston rod 46 carrying a piston 47 which reciprocates in the cylinder of the ram.

In addition to the hydraulic rams for raising and lowering the blade 30 rams 48 and 49 by 20 which the blade 30 may be swung around the axis of the king pin 28 are provided. These rams are pivotally mounted on brackets 50 at their rear ends, which brackets are carried by the thrust bars 20 and 21. The rams include pistons 51 connected with piston rods 52 which in turn 25 are connected to the ends of the scraper blade 30 by pivot pins 53. The rams 44 and 45 are pivoted to brackets 54 carried by the uprights 31. A connection between the ram cylinders and the brackets 54 is made by pins 55. The rams 44 and 30 45 and 48 and 49 are operatively connected with 35 a hydraulic control system as shown in Fig. 2, but more clearly disclosed in the diagram, Fig. 3. Here it will be seen that a tank 56 is provided to receive an incompressible fluid which tank is drawn off through a pipe 57 by a pump 58. The 40 pump is provided with a pipe 59 leading to the housing of a master valve 60. Within this valve housing is a rotary valve member formed with a central fluid passageway 61 and opposite side 45 fluid passageways 62 and 63. The passageway 61 extends diametrically across the rotary valve element and may establish communication between the pipe 59 and a pipe 64 leading to a secondary control valve 65 which will be hereinafter described. The central passageway 61 of the 50 valve element in the master valve housing 60 may be rotated to establish communication between the passageway 61 and a pipe 66 or a pipe 67, in which event either of the pipes 66 or 67 will be placed in communication with the pipe 64. The pipe 67 leads to one side of a relief valve 68. The other side of this valve connects with pipe 66. The pipe 66 also communicates with a pipe 69 leading to the housing of a reversing valve 70. 55 The reversing valve has a rotary valve element therein forming valve passageways 71 and 72. This rotary valve element may thus simultaneously establish communication between the pipe 69 and a pipe 73, and a pipe 74 and a pipe 75. It may also be desirable to rotate the valve to 60 establish communication between pipes 73 and 75, and pipes 69 and 74. The pipe 73 leads to the end of the ram 45. The pipe 74 connects with the opposite end of the same ram. The pipe 75 65 leads to one end of ram 44. This ram has a return pipe 76 which connects with the pipe 67. By this arrangement it will be evident that by the control of the master valve 60 and the reversing valve 70 the direction of flow through 70 the rams 44 and 45 may be alternately established, at which time the fluid displaced by piston 47 in the initially actuated ram will be carried through the valve 70 to the opposite ram and the fluid displaced from that ram will be 75 returned through the valve 60 to the tank 56.

This return will be effected through pipe 64 and the secondary valve 65 to a return pipe 77. This operation will take place when the secondary valve 65 is disposed with the central passageway 78 of its rotary valve member in simultaneous 5 register with pipes 64 and 77. The rotary valve element of the secondary valve 65 also has passageways 79 and 80 by which a fluid circulation may be completed when the passageway 79 is in communication with either of pipes 81 or 82. 10 The pipe 81 is here shown as connecting to one end of the hydraulic ram 48. The pipe 82 is here shown as connected to the same end of the hydraulic ram 49. The two rams are cross connected at their opposite ends by a pipe 83 so that 15 fluid delivered to either of the rams will move the piston within the ram to which it is delivered and thereafter displace fluid upon the opposite side of this piston to move into the opposite ram and thus simultaneously operate the same in a 20 reverse direction.

In operation of the device it is assembled as shown in the drawings and the hydraulic system is particularly connected as shown in Fig. 3. Assuming that the rotary element of the master 25 valve 60 is disposed with the passageway 61 in communication with the pipe 66 the pressure fluid will pass through pipe 66, thence through passageway 69 to passageway 72 of the rotary valve 70 when the valve is in dotted line position and 30 then through pipe 73 to the hydraulic ram 75. This will move the piston 47 of that ram outwardly and will displace fluid on the opposite side thereof forcing it through pipe 74 into passageway 71 of the valve 70, and thence through the 35 pipe 75 to the rear end of the hydraulic ram 44, thus moving the piston 47 of that ram outwardly, after which the displaced fluid in ram 44 will return through pipe 76 to pipe 67 and will be exhausted from the master valve 60 through the 40 passageway 63 leading to the pipe 64. This will force outwardly on the upwardly extending legs of the bell cranks 35 and 36 and will lower the blade 30. In the event it is desired to raise the 45 blade 30 the rotary valve element of the master valve 60 is rotated so that the passageway 61 thereof communicates with the pipe 67. Fluid will then flow in a reverse direction from that 50 previously described, passing along pipe 76 to the outer end of the hydraulic ram 44 and then moving the piston 47 of that ram rearwardly, at which time the displaced fluid will pass through pipe 75, the passageway 71 in valve 70, and thence along pipe 74 to the outer end of the hydraulic ram 44, moving that piston rearwardly and the 55 displaced fluid in advance thereof into pipe 73, after which it flows through passageway 72 of the valve 70, and then along passageway 69 to pipe 66 where it will be exhausted into the pipe 64. This action will swing the bell cranks 35 and 36 in a reverse direction and lift the blade. It 60 may be desirable to tilt the blade transversely. This may be done by moving the rotary valve element of the valve 70 to the position indicated in full lines at which time the establishment of fluid flow from the supply pipe 59 through the master valve 60 to either pipe 66 or 67 will produce an alternate delivery of the fluid first to the outer end of one hydraulic ram, following to the opposite end of the other hydraulic ram, or vice 65 versa, in which event the pistons 47 of the two rams will move in opposite directions and will produce the desired tilt. When this has been accomplished the rotary valve member of the master valve 60 will be returned to its original 70 75

position allowing a direct flow of fluid from the pump 58 through pipe 59 to the pipe 64. In making this adjustment it will be evident that the fluid displaced from the rear side of one piston 47 will be unequal with relation to the fluid displaced at the forward side of the opposite piston. This displacement would cause an unequal movement of the bell cranks 35 and 36 if it were not for the fact that the upper leg of bell crank 36 is longer than the upper leg of bell crank 35. When the bell cranks swing they will raise or lower the links 38 and simultaneously the rams 44 and 45 will swing vertically from the pivots at their rear ends.

When it is desired to swing the blade 30 laterally around the king pin 28 the master valve 60 is disposed in its vertical position to permit a flow of fluid from the pump 58 through pipe 59, and the valve 60 to pipe 64. The valve 65 may then be rotated to either of its opened positions to selectively establish a fluid flow to either pipe 81 or pipe 82. In either instance fluid will flow to one of the hydraulic rams 48 or 49, and the displaced fluid will flow through pipe 83 to the other hydraulic ram, thus making it possible to forcefully apply pressure to one end of the blade 30 while applying a drawing action to the opposite end. When the rotary element of valve 65 is returned to its neutral position the rams 48 and 49 will be locked and the blade 30 will in turn be rigidly held at a set angle which will not be disturbed until fluid is admitted to one or the other of pipes 81 or 82 by the valve 65. When the valve 65 is in its neutral position and the master valve 60 is in its neutral position a free flow of pressure fluid from the pump 58 may be had through pipe 77 to the storage tank 56.

It will thus be seen that by the structure here disclosed it will be possible to hydraulically control the elevation, tilt, and angular displacement of the scraper blade 30.

While I have shown the preferred form of my invention, as now known to me, it will be understood that various changes might be made in the combination, construction, and arrangement of parts, by those skilled in the art, without departing from the spirit of the invention as claimed.

Having thus described my invention what I claim and desire to secure by Letters Patent is:

1. A hydraulically operated scraper and the like, comprising a main frame, a running gear including a pair of track laying units, one disposed on each side of the main frame, a scraper blade disposed in advance of the main frame and transversely thereof, a frame structure for the scraper extending transversely of the main frame and along the opposite sides thereof, an equalizer bar connected to the rearwardly extending frame portions and transversely of the main frame structure, means articulately connecting said equalizer bar with the main frame, separate lever means supported by the separate track laying units of the machine, one end of each of said levers being articulately connected to the blade supporting frame, hydraulic rams one mounted on each of said track laying units and being provided with a piston rod pivotally connected to the opposite end of each of said levers, said rams having pressure chambers on either side of said piston, means for supplying fluid under pressure to the pressure chambers of the rams, fluid connections for the rams to deliver fluid under pressure to an end of one ram and to displace the fluid within said ram and deliver said fluid to

the opposite end of the other ram, and means embodied in the lever structures whereby simultaneous and uniform lifting of the blade frame will be accomplished while compensating for unequal movement of the pistons of the two rams due to the unequal capacities of the ram cylinders on opposite sides of their pistons.

2. A dirt moving machine including a tractor, a material moving member disposed transversely of the tractor, means articulately supporting the material moving member with relation to the tractor whereby the blade and the articulate support may be free to be bodily raised or lowered, or to be longitudinally tilted as a unit, a pair of hydraulic rams of equal fluid capacity having pressure chambers on both sides of their pistons, said rams being carried by the tractor and connected to the articulate support, a source of fluid under pressure therefor, connections between the source of fluid under pressure and the rams, and connections between the rams whereby the pistons of the rams may simultaneously move in opposite directions due to the delivery of the pressure fluid to one of the rams and the delivery of displaced fluid from said first mentioned ram to the opposite end of the second mentioned ram, and lever means connecting operative parts of the ram with the material moving member, said lever means acting to compensate for differences in movement of the moving parts of the two rams due to the differences in volumes of the pressure fluid introduced into one ram and the displaced fluid introduced into the other ram.

3. A dirt moving machine including a tractor, a material moving member disposed transversely of the tractor, means articulately supporting the material moving member with relation to the tractor whereby the blade and the articulate support may be free to be bodily raised or lowered, or to be longitudinally tilted as a unit, a pair of hydraulic rams of equal fluid capacity having pressure chambers on both sides of their pistons, said rams carried by the tractor and connected to articulate support, a source of fluid under pressure therefor, connections between the source of fluid under pressure and the rams, and connections between the rams whereby the pistons of the rams may simultaneously move in opposite directions due to the delivery of the pressure fluid to one of the pressure chambers of the rams and the delivery of displaced fluid from the other pressure chamber of said first mentioned ram to the opposite end of the second mentioned ram, lever means connecting operative parts of the ram with the material moving member, said lever means acting to compensate for differences in movement of the moving parts of the two rams due to the differences in volumes of the pressure fluid introduced into one ram and the displaced fluid introduced into the other ram, and selective means for alternately directing the pressure fluid to one of the rams and the displaced fluid to the other of said rams.

4. A dirt moving machine including a tractor, a material moving member disposed transversely of the tractor, means articulately supporting the material moving member with relation to the tractor whereby the blade and the articulate support may be free to be bodily raised or lowered, or to be longitudinally tilted as a unit, a pair of hydraulic rams of equal fluid capacity and having pressure chambers on both sides of their pistons, said rams being carried by the tractor and connected to the frame, a source of fluid under pressure therefor, connections be-

tween the source of fluid under pressure and the rams, and connections between the rams whereby the pistons of the rams may simultaneously move in opposite directions due to the delivery 5 of the pressure fluid to one of the rams and the delivery of displaced fluid from said first mentioned ram to the opposite end of the second mentioned ram, lever means connecting operative parts of the ram with the material moving member, said lever means acting to compensate for differences in movement of the moving parts of the two rams due to the differences in volumes of the pressure fluid introduced into one ram and the displaced fluid introduced into 10 the other ram, selective means for alternately directing the pressure fluid to one of the rams and the displaced fluid to the other of said rams, and a master valve for simultaneously actuating the two rams in unison in their previously set positions.

5. A hydraulically operated dirt moving machine comprising a tractor, a material moving member disposed transversely thereof, means articulately connecting said material moving member to the tractor for raising and lowering movement and for longitudinal tilting, a pair of hydraulic rams of equal capacity having pressure chambers on either side of their pistons carried by the tractor and connected to the articulate support, each including a cylinder, a piston reciprocating therein, and a piston rod extending from one end thereof, a source of fluid under pressure, a control valve in communication therewith, piping by which communication is established between the control valve to the opposite ends of both of the rams, and by which the opposite ends of one ram may communicate with the ends of the other ram, a second valve interposed in the lines of flow of the pressure fluid whereby the fluid may be directed simultaneously to the same end of both rams, or alternately to opposite ends of either ram, and whereby the displaced fluid from one ram may be introduced into a selected end of the other ram, and lever means connecting the pistons with the material moving member to adjust the same, said lever means being designed to compensate for action of the two pistons when the pressure fluid delivered to one cylinder differs in volume from the displaced fluid delivered to the other cylinder.

6. A dirt moving machine comprising a tractor, a pair of track laying units at opposite sides of the tractor and forming a running gear therefor, said units being pivoted for vertical swinging movement at the rear thereof and each including a rigid frame, a transversely disposed scraper blade mounted in advance of the tractor, an upright carried by each frame of a track laying unit, a pivot link pivoted adjacent the front of each frame of the track laying unit and extending vertically, a longitudinally extending member pivoted at its rear end to the upright and adjacent its forward end to the vertical link, a bell crank pivotally mounted at the forward end of each of said longitudinally extending members, a frame structure by which

the scraper blade is articulately supported from the tractor, links connecting one leg of each bell crank with said frame structure, the legs of said bell cranks being of unequal length and operating means of unequal movement carried by the upright of each of the track laying units, said operating means being of unequal length and connected to the opposite leg of each of the bell cranks to swing the same, the unequal length of the operated means and the bell cranks compensating for the unequal movement of the operating means.

7. In a dirt moving machine, a tractor, a scraper blade disposed transversely of said tractor, a frame by which the blade is articulately connected to the tractor in advance thereof, a pair of hydraulic rams connected to the tractor and the frame for lifting and lowering movement and tilting movement with relation to the tractor, and a second pair of hydraulic rams carried by the frame and pivotally connected to the opposite ends of the blade whereby the blade may be angularly adjusted independently of the movement of the frame, said rams being characterized as having power chambers on either side of their pistons, a source of fluid under pressure, means connecting said rams and the source of fluid supply, valve means for each pair of hydraulic rams whereby each pair of rams may be operated independently or in unison or the source of fluid supply may be connected to the same end of both rams or to the opposite ends of the rams of the first pair and the pressure fluid may be delivered to opposite ends of the second pair.

8. A hydraulically operated dirt moving machine comprising a tractor, a material moving member disposed transversely thereto, means articulately connecting said material moving member to the tractor for raising and lowering movement and for longitudinally tilting, a pair of hydraulic rams of equal capacity having pressure chambers on either side of their piston carried by the tractor and connected to the articulate support, each including a cylinder, a piston reciprocating therein and a piston rod extending from one end thereof, a source of fluid under pressure, a control valve in communication therewith, conduits by which communication is established between the control valve and the opposite ends of both of the rams and by which the opposite ends of one ram may communicate with the other end of the other ram, a second valve interposed in the lines of flow of the pressure fluid whereby the fluid may be directed simultaneously to the same end of both rams or alternately to opposite ends of either ram whereby the displaced fluid from one ram may be introduced into the selected end of the other ram, a lever means connecting the pistons with the material moving member to adjust the same, said lever means being of unequal length to compensate for action of the two pistons when the pressure fluid delivered to one cylinder differs in volume from the displaced fluid delivered to the other cylinder.

CHARLES LE BLEU.
